UNITED STATES PATENT OFFICE.

GEORGE W. PRENTICE, OF PROVIDENCE, RHODE ISLAND.

BUTTON-FASTENER.

SPECIFICATION forming part of Letters Patent No. 379,028, dated March 6, 1888.

Application filed September 29, 1887. Serial No. 251,028. (No model.)

To all whom it may concern:

Be it known that I, GEORGE W. PRENTICE, a citizen of the United States, residing at Providence, in the county of Providence and State of Rhode Island, have invented certain new and useful Improvements in Button-Fasteners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to button - fasteners, more particularly of the two-prong or staple class; and it consists of a metallic fastener having the wire or stock forming the portion lying above the fabric or material (when secured thereto) of the normal size, and having the prongs thereof concavo-convex in cross-section.

Heretofore, so far as I am aware, each wire or blank forming a fastener has been substantially uniform in cross-section throughout its 25 length, thereby, when angular stock is employed, producing sharp edges which are more or less irritating to the wearer when such fasteners are used for securing buttons to shoes.

The foregoing disadvantage I seek to overcome by swaging or otherwise flattening the prong portion of the fastener into a concavo-convex form, the convex side of the prong obviously being next the wearer in use.

Another advantage resulting from my improvement is that the prongs penetrate the fabric or leather more easily and are more readily clinched thereunder than is possible in fasteners where the prongs are exposed portions are alike in cross-section.

40 In the drawings illustrating my improvements, Figure 1 represents in perspective a series of staple or two-prong fasteners, the upper or head portion thereof, including the form of the wire from which the fasteners are made, being common and well known. The lower or prong portion of each fastener, however, is made thinner and swaged into a concavo-convex form in cross section, as indicated by the section *c*, taken on lines *x x*. The broken line 45 *o o* indicates the line of upper surface of the material or fabric to which the fasteners may

be secured. Fig. 2 represents enlarged cross-sectional views of wire or stock which may be used for the staples. Fig. 3 is a plan view of a piece of wire adapted to be bent to form a 55 two-prong fastener, the two end portions being flattened and the central or intermediate portion remaining normal. Fig. 4 is a cross-sectional view of the wire taken on line *o o*. Fig. 5 is a similar view taken on line *x x*, showing 60 the wire swaged into a concavo-convex form; and Figs. 6 and 7 represent views of a fastener formed from the wire shown in Fig. 3 and secured to a fabric, a button being retained in the head of the staple.

65 As hereinbefore stated, the wire *b* in cross-section may be of any desirable or practicable form, as usual.

In the making of a fastener, *a*, a length of wire is first cut off. The two end portions are 70 then submitted to a suitable press or swaging-machine, which gives to that portion of the wire the concavo-convex form *c* shown in the several figures. This latter operation necessarily expands the wire in a lateral direction, 75 so that the swaged part considerably exceeds that of the plain portion. Practically I prefer that the swaged portion shall extend the length of the prongs, as shown in Fig. 1. To facilitate the entrance of the prongs into the 80 fabric, they may be pointed or sharpened, as indicated at *m* by the full lines, Fig. 3.

The manner of attaching buttons to fabrics by means of staple-fasteners is well known. An implement for mechanically attaching them 85 consists of a pivoted jaw member adapted to retain the button and fastener in position, while another jaw provided with suitable clinching-dies is actuated to force the flattened prongs through the fabric and clinch them 90 thereunder, the rounded or convex surface being exterior and the concave surface in contact with the fabric, as shown in Figs. 6 and 7.

I claim as my invention—

1. The button - fastener staple herein described having its upper or head portion substantially uniform in cross-section, and having its prongs or clinching portion broader than said upper or head portion and concavo-convex in cross-section, substantially as shown 100 and specified.

2. The button - fastener staple herein de-

scribed having prongs concavo-convex in cross-section, and having the fastener intermediate of the prongs narrower than said prongs and bent to retain the eye of a button, and of the 5 normal shape of the wire, substantially as hereinbefore described.

3. The button - fastener staple herein described having the upper portion thereof uniform in cross-section with the wire or blank 10 from which it is made and adapted to retain the eye of a button, and having the prongs or

legs broader than said upper portion and bent or shaped to a concavo - convex cross-section throughout their length, and terminating in points adapted to readily penetrate the fabric, 15 substantially as specified.

In testimony whereof I affix my signature in the presence of two witnesses.

GEORGE W. PRENTICE.
